VENTILATED AWNINGS

David L. Schurger, Dallas County, Tex.

Application November 9, 1953, Serial No. 390,992

2 Claims. (Cl. 20—57.5)

This invention relates to new and useful improvements in ventilated awnings.

One object of the invention is to provide an improved ventilated awning having spaced louvers formed free from sharply bent marginal portions which, while lending themselves to sheet metal structure, are especially adapted to be constructed of suitable plastic material.

A further object of the invention is to provide an improved ventilated awning having upright frame members adapted to be attached to a building at a window or door opening and including an inclined supporting member having integral brackets struck therefrom and bent at different elevations to support louvers in spaced, ventilating relation, whereby a more stable and less expensive awning is produced.

Another object of the invention is to provide an improved ventilated awning having a plurality of transverse overlapping louvers of such construction and so mounted that the same may be formed of suitable plastic material, whereby the appearance and translucence of the awning are enhanced without detracting from its durability, rigidity and light-weightness.

A still further object of the invention is to provide an improved ventilated awning having transverse louvers and upright supporting frame members carrying brackets of varying elevations adapted to rigidly hold the louvers in spaced, ventilating order and permitting the erection of a relatively flat canopy or roof, when desired, with adequate drainage.

Still another object of the invention is to provide an improved awning including transverse louvers having contiguous edge portions formed to overlap and shaped so that the longitudinal edge of the underlying louver has an upstanding hump and the overlying longitudinal edge of the adjacent louver has a flange overhanging the hump so as to deflect and prevent a direct passage of air between each hump and flange while allowing an undulating flow of air between the louvers.

A further object of the invention is to provide an improved awning which has transverse, spaced individual louvers mounted on end supports in such a manner as to permit an adequate flow of air between the ends and longitudinal edges of the louvers.

A construction designed to carry out the invention will be hereinafter described, together with other features of the invention.

The invention will be more readily understood from a reading of the following specification and by reference to the accompanying drawings, wherein examples of the invention are shown, and wherein:

Fig. 1 is an exploded, perspective view of the elements constituting an awning constructed in accordance with the invention,

Fig. 2 is a perspective view of an assembled awning,

Fig. 3 is an enlarged, perspective view of a portion of one of the frame members,

Fig. 4 is a perspective view of one end portion of a

2

canopy-type of awning having an outer corner portion broken away to show underlying structure,

Fig. 5 is an enlarged, perspective view of one outer corner of a frame for a canopy-type of awning,

Fig. 6 is an end elevational view of a door hood type of awning,

Fig. 7 is a side elevational view of a standard window type of awning, a portion of one end being broken away to show underlying frame structure, and

Fig. 8 is an enlarged, side elevational view of an end portion of the awning with the end removed.

In the drawings, the numeral 10 designates an upright frame member for an awning, generally, of a triangular shape and, preferably of metal or other suitable material.

15 In constructing an awning, upright frame members are provided at its ends and, depending upon the width and/or length of the awning, one or more intermediate frame members may be employed. Each frame member is substantially identical and triangular, but is subject to variation in shape as well as in height, width and/or length and outward extension or transverse projection.

Each frame member 10 includes, an upright, inner supporting or mounting element 11, an outwardly extending or transverse base or strut element 12 and an inclined supporting or carrying element 13 extending downwardly from the upper portion of the element 11 to the outer end of the strut element 12. Each supporting element 13 may include one or more breaks so that it has two or more inclinations although it can be made without a break.

30 The elements 11 and 12 are preferably formed of angle irons connected at their lower and inner ends by a screw or other fastening 14 and disposed at a right angle to each other. Preferably, the supporting element 13 is formed of an inverted channel having its upper end secured in the upper end of the angle iron 11 and held by a bolt or other fastener 15, while its lower end is fitted in the outer end of the angle iron 12 and secured by a bolt or other fastener 16, as is best shown in Fig. 5. For connecting the frame member 10, a horizontal brace or tie member 17, in the form of an inverted angle iron, is attached to the lower end of each channel 13 by a bolt or other fastener 18. The elements 10 to 18, inclusive, constitute an awning frame.

In Figs. 1 and 2, a casement type of awning is shown. Each channel 13 has its flanges 19 cut out so that it may be bent at 20 to form a gambrel-type of support with an upper section 21 of low pitch or slight upward inclination and a lower or front section 22 of much greater pitch or downward and outer inclination. A roof or front panel 23 is formed of overlapping transverse, elongate louvers or slots 24. Each louver is of substantially the same size and shape and is disposed in underlapping and overlapping, spaced relation to adjacent louvers, above and below. It is desirable to form each louver 24 of plastic material, but other materials, such as metal may be used. The advantages of plastic material, such as polyester resins reinforced with glass fiber mats, are many and among such advantages are that, being colorful in various translucent tints, cool and non-glare illumination is admitted to a room and presents an attractive exterior appearance as well as forming a barrier to a large percentage of the sun's heat rays. The louvers, being mounted in overlapping and spaced relation, permit a passage of air therebetween and assure adequate ventilation. Louvers of such material are not subject to ordinary breakage and are not injured by acids, grease, cigarettes, fire sparks, hail and rust.

60 As shown most clearly in Fig. 8, each louver 24 has a general arcuate, transverse contour and is bowed or curved outwardly or upwardly at its longitudinal medial portion 25 upon a relatively large radius with its lower margin terminating in a downwardly-curved lip or flange.

26. An upstanding, substantially semi-circular bead or hump 27 is formed on the upper margin of the louver by reversely curving said margin upwardly and then downwardly upon itself. Intermediate its curvature 25 and bead 27, the upper portion of the louver is relatively flat as shown by the numeral 28. As will be apparent, the lip 26 is adapted to overlie the bead 27 of the adjacent louver in spaced relationship. For mounting the louvers, the web 29 of each channel 13 is provided with upstanding, angular brackets 30 and 31 arranged in opposed pairs (Fig. 3). The brackets are formed by cutting the web along three sides of said bracket as shown at 32 and 33 and bending the cutouts upwardly and then downwardly upon themselves at substantially right angles to provide flanges or shoulders 34 and 35 directed toward each other with the cutouts 32 and 33 between each pair of brackets. Openings 36 and 37 are formed in the bracket flanges for receiving suitable screws or other fasteners 38. While the outer or lower bracket 30 of each pair is relatively tall and almost right angular and has its flange 34 nearly parallel to the channel web 29 for mating with the curved portion 25 of the louver, the inner or upper bracket 31 is relatively short and has its flange 35 extending at an obtuse angle to said web for conforming to the relatively flat portion 28 of said louver. Manifestly, the louvers 24 seat upon the flanges and are secured thereto by the screws 38 engaging in the openings 36 and 37. It is noted that each louver is supported with its upper substantially flat portion 28 bearing against the webs 29 of the channels 13, whereby its head 27 underlies and is spaced from the overhanging lip 26 of the adjacent higher louver. The spacing between the louvers provides air openings which extend transversely across the panel 23 and afford adequate ventilation. The overhang of each lip 26 with respect to the upstanding head 27 thereunder provides sufficient protection against the passage of wind-blown rain and other moisture.

Although the frame members and roof or front panels are subject to variation, the construction and mounting of the louvers 24 remains virtually unchanged. While the frame member 10 is for a casement-type awning, modified frame members 39, 40, and 41 may be provided for a canopy (Figs. 4 and 5) a door hood (Fig. 6) and a conventional awning (Fig. 7). Instead of or in addition to the break 20 and upper section 21 of the supporting element 13, the frame members 39 and 40 have breaks 42 and 43 adjacent the outer ends of their corresponding elements to provide lower sections 44 and 45 which are abruptly inclined. As shown, the main portions of these members have appreciably less inclination of pitch than the element 13 and the upper section 21 preferably is omitted. The frame member 41 has a similar break 46 and an upright lower section 47 (Fig. 7). Since the other elements of the frame members are identical, except for inclination, the same numerals are employed. In each instance, the louvers 24 are mounted on the frame members in the same manner with a single louver being carried by the upper section 21 and lower sections 44, 45 and 47. When the projection of the awning is considerable, additional supports may be required. A corner post or upright 48 may have its upper end secured to the outer end of the frame member 39 at the lower end of its section 44 (Fig. 4) or a transverse support, in the form of an inverted channel 49 may be suitably attached to said member immediately above its break 42. As shown in Fig. 5, one or more upright posts or standards 50 may be engaged in and fastened to the channel 49.

End or side panels for the awnings may assume various forms or may be omitted entirely, as in the case of canopy for a patio or a car port. In Figs. 1, 2 and 7, the side panels are formed of louvers 51 and 52 conforming to their respective frame members 10 and 41 and similar to the louvers 24. If desired, side panels 53, of ex-

panded metal or other foraminous material, may be used as shown in Figs. 4 and 6. For fastening the louvers 50 and 51 to the frame members, bolts 54 are provided and spacers 55 are carried by the lower bolts of said louvers to space the lips 26 at their lower margins from the underlying upper edge portions of adjacent louvers. The panels 53 may be fastened directly to the outer surfaces of the end frame members by suitable bolts 56.

The awnings are easily installed and removed, and, because of the elongated, transverse openings between the louvers, sufficient passage of air for ventilation is provided. By use of plastic material, the surfaces of the awnings are relatively smooth and offer little obstruction for the collection of dirt and soot. The structural arrangement while simple is sturdy and offers an advance in the art. It will be observed that, due to the curvature and stepped mounting of the louvers, a roof of low pitch may be constructed and rain and snow water adequately drained. While the spacing between each lip 26 and head 27 is ample to provide adequate ventilation, it is nevertheless restricted and there is no direct passage between the louvers. The brackets 30 and 31, being of relatively thin metal and being spaced apart, offer little resistance to the passage of air between the channels and louvers and air currents may flow in from the ends as well as from the front of the awning.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A rigid awning including frame members each having an inclined inverted channel support, angular brackets 35 bent outwardly from the upper surface of the channel support, the brackets being disposed in pairs, and elongate louvers bowed outwardly transversely and each having a down-turned flange on one longitudinal edge and an up-standing hump on its opposite longitudinal edge, the brackets of each pair being spaced apart and one bracket being of less outward projection than the other bracket, the bowed portion of one of the louvers overlying and being fastened to each pair of brackets inwardly of its flange and hump and spaced from the channel support 40 according to the projection of each bracket, whereby said louvers are held with their humps underlying and spaced from the flanges of the adjacent louvers.

2. A rigid awning including inclined frame members having upper longitudinal surfaces, angular brackets integral with and extending outwardly from the upper longitudinal surfaces of the frame members and disposed in coacting pairs, the brackets of each pair being of unequal heights, and an elongate louver overlying and rigidly secured on each pair of brackets and disposed at a transverse inclination to said longitudinal surfaces, the longitudinal edge portions of each louver being spaced from the brackets and from the longitudinal edge portions of adjacent louvers.
